UNITED STATES PATENT OFFICE.

FRIEDRICH HAARMANN, OF ESSEN, GERMANY, ASSIGNEE TO FRIED. KRUPP AKTIEN-
GESELLSCHAFT, OF ESSEN-ON-THE-RUHR, GERMANY.

DEVICE FOR CLOSING THE TAP-HOLES IN SMELTING-FURNACES.

1,401,072.

Specification of Letters Patent. Patented Dec. 20, 1921.

Application filed September 4, 1920. Serial No. 408,390.

To all whom it may concern:

Be it known that I, FRIEDRICH HAARMANN, residing at Essen, Germany, a citizen of the German Republic, have invented a certain new and useful Improvement in Devices for Closing the Tap-Holes in Smelting-Furnaces, (for which I have filed application in Germany, Sept. 6, 1918,) of which the following is a specification.

10 This invention relates to a device for closing the tap hole in smelting furnaces by means of a pivotally mounted arm, which carries a plug, and which arm is so moved, that the plug is only plunged toward the end 15 of its closing movement into the metal issuing from the tap hole of the furnace.

The object of the invention is to provide a device of this kind which shall be as simple as possible and work reliably.

20 The invention will be further described with reference to the accompanying drawing which shows a side elevation of a construction of the device diagrammatically according to the invention.

25 In the wall A of the furnace is arranged the tap hole a^4 , which establishes connection between the smelting chamber a^2 and the discharge chute a^3 . To the external surface of the furnace or frame a^4 is fixed a bearing device a^5 , to which a crank arm or link B is pivotally connected by means of a pin a^6 . In the bearing device a^5 is also mounted a shaft C, which carries a crank arm C^1 rigidly connected thereto. The two crank arms B 30 and C^1 are pivotally connected at their ends remote from the bearing device a^5 by pins b^1 and c^2 to a coupling member D so forming a quadrilateral. The coupling member 35 D has an extension D^1 pointing toward the tap hole a^4 of the furnace to the free end of which is fixed a spike d^2 on which is mounted the plug not shown in the drawing. The shaft C carries finally an arm c^3 to which a handle E is pivoted, and also another arm 40 c^4 to which is attached a counterweight F.

When the tap hole is open, the parts assume the position shown by dot and dash line in the drawing in which they are held by the counterweight F. When the tap hole 45 is to be closed, the plug, which is composed of clay or the like, is placed on the spike d^2 and then the entire device swung downward by pulling down the handle E. In its de-

scent the plug moves over a steep downward path shown by dot and dash lines in the drawing and plunges only toward the end of its closing movement into the metal issuing from the tap hole.

Claims.

1. A device for closing the tap hole of smelting furnaces comprising a frame, a crank arm mounted thereon, a rod pivotally connected to said crank arm at a point lying between the ends of the rod, a plug for closing said tap hole secured on the one end of said rod, and means movably connecting the other end of the rod to said frame.

2. A device for closing the tap hole of smelting furnaces comprising a frame, a crank arm mounted thereon, a rod pivotally connected to said crank arm at a point lying between the ends of the rod, a plug for closing said tap hole secured on the one end of said rod, and a second crank arm mounted on said frame at a distance away from said first-named crank arm and pivotally connected to the other end of said rod.

3. A device for closing tap holes of smelting furnaces comprising a frame, a rod and a plug mounted on said rod, and a dual link connection between said rod and frame with the dual links substantially parallel for movably controlling the movement of said rod and plug relative to said frame.

4. A device for closing tap holes of smelting furnaces, comprising a frame, a rod and a plug mounted on said rod, two link connections between said rod and frame forming a four sided figure with the rod side of said linked figure forming an acute angle with said frame.

5. A device for closing tap holes of smelting furnaces, comprising a frame, a rod and a plug mounted on said rod, two link connections between said rod and frame forming a four sided figure with the rod side of said linked figure forming an acute angle with said frame, two of the sides of said four sided figures being of unequal length.

The foregoing specification signed at Essen, Germany, this 15th day of June, 1920.

FRIEDRICH HAARMANN.

In presence of—

HANS GOTTMANN,
JOSEF ALBERTZ.
